UNITED STATES PATENT OFFICE.

CHRISTOPH ALEX, OF CHICAGO, ILLINOIS.

BLOW-GUN.

SPECIFICATION forming part of Letters Patent No. 239,683, dated April 5, 1881.

Application filed August 23, 1880. (No model.)

To all whom it may concern:

Be it known that I, CHRISTOPH ALEX, of Chicago, in the county of Cook and State of Illinois, have invented a certain new and useful Improvement in Blow-Guns, of which the following is a specification.

The object I have in view is to produce a toy gun wherein the missile will be projected by means of blowing, which gun will enable the juvenile marksman to take aim, will throw the missile a considerable distance without great effort on the part of the operator, and will at the same time be simple and cheap in construction.

My invention consists in the peculiar novel devices and combinations of devices employed by me, as fully hereinafter explained, and pointed out in the claims.

In the accompanying drawings, forming a part hereof, Figure 1 is a perspective view of the toy gun; Fig. 2, a longitudinal section of the barrel of the same on the line of the blow-tube, the stock being in elevation; and Fig. 3, a separate view of the removable mouth-piece.

Like letters denote corresponding parts in all the figures.

A is the stock of the gun, and B the barrel, both made of wood. The stock is shaped to fit the shoulder, and has somewhat more rise to the barrel than usual, in order to give room for the position of the head when projecting the missile.

The barrel B is made in two halves, *a b*, the lower half being in one piece with the stock, while the upper half terminates at the breech of the gun. The two halves *a b* of the barrel are grooved to form a long tube, C, extending from the muzzle of the barrel through the breech of the same. The halves of the barrel are secured together by straps *c c'*, which may have points turned up to form sights.

In the breech of the gun is inserted a short metal tube, *d*, permanently secured therein. *D* is another short tube, which slides removably within the tube *d* into the breech of the gun. This tube *D* has an offset, *e*, at its outer end, to which is attached a flaring mouth-piece, *f*, such mouth-piece being located by means of

the offset below and to one side of the barrel. The tube *D* has an opening, *g*, in its side, through which the missile is inserted into such tube, the opening being within the gun when it is operated. The tube *d* serves to make a close fit with the removable tube *D*, so that the full force of the blast of air will be utilized.

To use the toy gun the tube *D* is removed and the missile is placed therein through opening *g*. Then the tube is pushed into the breech of the gun, the mouth-piece at the same time being adjusted to the proper position. The gun is then raised to the shoulder, the lips are put to the mouth-piece, and the eye of the marksman glances along the barrel. When the object is in proper range he blows into the mouth-piece, and the missile is projected from the gun. The gun can then be reloaded, as before described.

The offset in the pipe *D* permits the mouth-piece to be located so that the gun can be aimed at the same time that it is operated.

The features of construction before described could also be applied to toy pistols without departing from the spirit of my invention.

What I claim as my invention is—

1. In a toy blow-gun, the combination, with the stock and the barrel having a blow-tube, of the removable tube *D*, having offset *e* and mouth-piece *f*, and provided with the opening *g*, through which the missile is placed in such tube *D*, said opening *g* being inclosed within the blow-tube when the parts are in position for ejecting the missile, substantially as described and shown.

2. In a toy blow-gun, the combination, with the stock, of the barrel, made in two longitudinal pieces, of wood, grooved and secured together so as to form the blow-tube *C*, the metal tube *d* in the end of the blow-tube, and the removable tube *D*, having mouth-piece, and projecting into such tube *d*, substantially as described and shown.

CHRISTOPH ALEX.
